UNITED STATES PATENT OFFICE.

CHARLES F. STAUDENMAYER, OF BALTIMORE, MARYLAND.

GAME.

1,410,618.

Specification of Letters Patent. Patented Mar. 28, 1922.

Application filed January 25, 1921. Serial No. 439,877.

To all whom it may concern:

Be it known that I, CHARLES F. STAUDENMAYER, a citizen of the United States, residing at Baltimore, State of Maryland, have 5 invented a new and useful Game, of which the following is a specification and the accompanying drawing, forming a part of the same.

My invention relates to improvements in 10 games and has for its object to provide an instructive and interesting game apparatus.

Fig. 1 is a plan view of the game embodying this invention;

Fig. 2 is a side elevation, partly in section of game shown in Fig. 1.

Fig. 3 is also a side elevation showing the easily adaptability of game to a vertical plane by means of any suitable support fastened to base of game hereinafter described.

20 Referring to the drawing the numeral 1, designates a base of hollow cylindrical construction, with a bottom wall to which are attached a plurality of supports 2, and to center of which is inserted a pivot pin 3, 25 with a lateral flange, and a semi-spherical top end 4 on which to balance and rotate disk 5. On the inside face of bottom of base there are symbols or characters 9, shown in Fig. 1 as Arabic numerals, but symbols 30 can be of any desired form and number.

The rotating disk 5 is of balanced construction, placed in proximity to inside face of bottom of base 1, with any desired number of holes 8 located in its face for the 35 sighting of symbols 9 on base 1. Disk 5 has at its center a turning knob 6 with a socket 7 for receiving semi-spherical top end 4 of pivot pin 3.

From the nature of the different kinds of 40 symbols that can be used and the number

and location of holes in rotating disk, the methods of play and number of players can be many.

One method of play would be for each player in turn to give the knob 6 a quick revolving motion. The disk 5 is thus set in motion on the semi-spherical end 4 of the pivot pin 3 in the base 1 for a space of time depending upon the momentum given the disk and when it comes to rest there may not 50 be any symbols as above described visible, or there may be one or more of said symbols visible through the sight holes 8 in the disk 5, as shown in Fig. 1 where the Arabic numeral 14 is visible, depending upon the location of the sight holes. The player who 55 after having a pre-arranged number of turns in rotating the disk and having the largest sum from amounts represented by the numerals visible at each turn of the disk would 60 be considered the winner.

Having thus described the invention, what is claimed as new is:

In a game, the combination with a base having a centrally disposed pivot pin, of a 65 disk having in its face a plurality of holes located in such manner that through them one or more symbols on the internal face of the bottom wall of the aforesaid base may be visible; and having at the center of the 70 disk a knob for turning the same, with a socket for receiving the pivot pin on the aforesaid base.

In testimony whereof, I have signed my name to this specification in the presence of 75 two subscribing witnesses.

CHARLES F. STAUDENMAYER.
